UNITED STATES PATENT OFFICE.

WILLIS HIRE, OF DETROIT, MICHIGAN.

ENVELOP.

1,339,392.

Specification of Letters Patent. Patented May 11, 1920.

Application filed August 26, 1919. Serial No. 318,937.

To all whom it may concern:

Be it known that I, WILLIS HIRE, a citizen of the United States, residing at Detroit, in the county of Wayne and State of Michigan, have invented new and useful Improvements in Envelops, of which the following is a specification.

This invention relates to envelops and has for its object the provision of an envelop 10 formed from a single piece of material so folded and secured as to provide a plurality of separate pockets or compartments, the specific arrangement of which is that they are adapted to contain different matter, 15 such as catalogues or circulars, it being possible to use circulars or catalogues of different sizes, especially as all the compartments are separate.

An important object is the provision of 20 an envelop of this character which is designed to form part of a new mailing system in which all the desired matter may be sent to an addressee in one cover so that the letter and also the catalogues and other 25 matter will reach their destination at the same time instead of at different times as is an annoying defect in the present system.

An additional object is the provision of 30 an envelop of this character which will be very simple and inexpensive in manufacture, highly efficient in use, and a general improvement in the art.

With the above and other objects and advantages in view the invention consists in 35 the details of construction to be hereinafter more fully described and claimed and illustrated in the accompanying drawings in which—

Figure 1 is a view of the blank from 40 which the envelop is formed.

Fig. 2 is a view showing the formation of the compartment adapted to receive first class matter,

Fig. 3 is a view showing the formation of 45 a second compartment, and

Fig. 4 is a view showing the formation of a third compartment.

Referring more particularly to the drawings I have shown the envelop as formed 50 from a single sheet of material 10 of substantially L-shape and including a relatively large body portion 11 and a relatively narrow elongated portion 12 extending from one edge thereof. The body portion 11 has 55 formed at one corner thereof a flap 13 carrying a securing member 14 adapted to be

engaged as hereinafter explained, with a securing member 15. At one edge the body portion 10 has formed thereon a gummed flap 16 and the opposite edge of the body 60 10 is gummed throughout its length, as shown at 17. The edge of the body 10 at a point spaced slightly from the flap 13, is provided with a concave cut 18.

The elongated strip portion 12 is provided 65 with a plurality of concave cuts 19 and has formed upon one edge a flap 20 carrying a securing member 21 adapted to be engaged with a securing member 22.

In the formation of the envelop the end 70 portion of the strip 11 is folded upon the line 23, the flap portion 20 is folded upon the line 24 and the securing members 21 and 22 are engaged. This formation is clearly shown in Fig. 2 and provides a compartment 75 open at the concave cut side for the reception of first class mail matter. This compartment is designated by the numeral 25 in Fig. 2. After this compartment is formed the strip portion 12 is folded upon the line 80 26 to lie upon the portion 11 and the flap 16 is folded over onto the compartment 25 and secured thereto by the gum. The space between the compartment member 25 and the body 11 constitutes another compartment 85 within which may be disposed printed circulars, a small book, or the like. It will be observed that even after the compartment 25 is in this position access may be had thereto by opening the flap 20. The formation of 90 the second compartment is clearly shown in Fig. 3. After the formation of the envelop has progressed this far, the body 10 is folded upon the line 27 and the gummed edge 17 is secured to the opposite side of the body 11. 95 This provides a third compartment, as will be clearly evident from an inspection of Fig. 4, within which may be disposed a larger booklet, such as a catalogue or the like. The flap 13 is then folded down and the securing members 14 and 15 engaged, whereupon all

100 members 14 and 15 engaged, whereupon all the parts of the envelop together with the matter contained therein will be held properly assembled.

105 From the foregoing description and a study of the drawing it will be apparent that I have thus provided an envelop from a single sheet of material so cut and folded as to provide a plurality of compartments within a single envelop whereby mail matter of different natures and classes may be sent under the same cover.

While I have shown and described the preferred embodiment of my invention it is of course to be understood that I reserve the right to make such changes in the form, 5 construction, and arrangement of parts as will not depart from the spirit of the invention or the scope of the subjoined claim.

Having thus described my invention I claim:

- 10 10 An envelop formed from a single sheet of material of substantially L-shape including a body portion, an elongated relatively narrow portion extending from one edge of said body portion, a flap member formed on 15 the edge of said body portion opposite the direction of extension of said narrow portion, engaging fastening member carried by said flap and said body portion, a gummed flap formed on one edge of said body por-

tion adjacent said narrow portion, and the 20 opposite edge of said body portion being gummed, a flap portion formed on one edge of said narrow portion at the outer end thereof, and interengaging securing means on said narrow portion and said last named 25 flap, said narrow portion being foldable onto itself and said last named flap being foldable whereby to define a relatively small compartment, said compartment being foldable onto said body portion with a gummed 30 flap sealed thereonto whereby to define a second relatively small compartment, and said body portion being foldable onto itself with the gummed edge thereof engaged against the opposite edge and said first 35 named flap being foldable whereby to define a third compartment of relatively large size.

WILLIS HIRE.
